(57) **CLAIM**

The ornamental design for a portable computer, as shown and described.

DESCRIPTION

FIG. 1 is a right, front, and top perspective view of a portable computer showing my design.

FIG. 2 is a front elevational view of the portable computer in FIG. 1.

FIG. 3 is a rear elevational view of the portable computer in FIG. 1.

FIG. 4 is a left-side elevational view of the portable computer in FIG. 1.

FIG. 5 is a right-side elevational view of the portable computer in FIG. 1.

FIG. 6 is a top plan view of the portable computer in FIG. 1.

FIG. 7 is a bottom plan view of the portable computer in FIG. 1.

FIG. 8 is a right, front, and top perspective view of the portable computer in FIG. 1 in a closed state.

FIG. 9 is a left, rear, and top perspective view of the portable computer in FIG. 1 in the closed state.

FIG. 10 is a right, front, and top perspective view of the portable computer in FIG. 1 with a display facing up; and, FIG. 11 is a left, rear, and top perspective view of the portable computer in FIG. 1 with the display facing up.

The broken lines shown in the drawings are included for the purpose of illustrating portions of the portable computer that form no part of the claimed design.

1 Claim, 11 Drawing Sheets
